Inventor:

Allen A. Lyon.

Milo B. Stevens & Co.

Attorneys

UNITED STATES PATENT OFFICE.

ALLEN A. LYON, OF BELVIDERE, ILLINOIS.

STONE STATUARY AND METHOD OF CONSTRUCTING SAME.

Application filed May 25, 1923. Serial No. 641,461.

To all whom it may concern:

Be it known that I, ALLEN A. LYON, a citizen of the United States, residing at Belvidere, in the county of Boone and State 5 of Illinois, have invented new and useful Improvements in Stone Statuary and Methods of Constructing Same, of which the following is a specification.

My invention relates to flower stands and 10 analogous articles of an ornamental character for outdoor decoration, having for its primary object the provision of an improved ornamental exterior surface formed by embedding pebbles, crushed stone or 15 other objects therein.

Another important object of the invention resides in a novel process for the production of such articles and embedding ornamental particles in the walls thereof.

20 A further object is to furnish an improved flower stand or receptacle of a hollow moulded construction produced by a novel and improved process.

A still further object of the invention is 25 the production of a flower stand of moulded construction which may be formed in sections, an improved means being used for connecting various ones of these sections together, for permitting communication between the interiors thereof.

The above and other objects are attained 30 by certain novel features and processes of construction as will be more fully set forth in the following description, and pointed out in the claims.

In order that the invention may be better understood reference is had to the accompanying drawings forming a part of this specification, and wherein a preferred embodiment of the invention is shown for the purpose of illustration.

In the drawings,

Figure 1 is an elevation of a completed stand constructed in accordance with my invention;

Fig. 2 is a central vertical section through a built-up mold showing a completed stand therein;

Fig. 3 is a sectional view showing the first molding frame and the first step in building the stand;

Fig. 4 is a fragmentary section of the first molding frame illustrating the second step in the formation of the base of the stand;

Fig. 5 is a view similar to Fig. 3 showing how the column of the stand is formed;

Fig. 6 is a sectional view taken through one of the frames illustrating the formation of the top of a column;

Fig. 7 is a sectional view showing the form for forming a pedestal and the support for the bowl;

Figs. 8 and 9 illustrate the means for forming the bowl of the stand;

Fig. 10 shows a plan view of one of the frames, and

Fig. 11 shows a plan view of the pedestal form and its supporting arms.

Referring specifically to the drawings, 70 wherein like reference characters designate like parts throughout the several views, 5 denotes one of the building frames, the same being best shown in Fig. 10, the walls 30 thereof being separably connected at 75 their ends by means of bolts or other similar fastenings 31.

In carrying out the invention, the frame 5 is placed upon a smooth surface and an inner frame 6 is placed therein, this frame 80 being of the desired form and dimensions for the base of the stand. The frame 6 having been placed within the frame 5, the space between the walls of the respective frames is filled to the top edge of the frame 85 6 with sand 7. The sand is firmly packed, whereupon the frame 6 is removed and the wall of sand 7 which is formed by the frame 6 is studded with crushed stone, pebbles or other ornamental particles which are desired for the outer surface of the base. This operation having been performed, concrete or other plastic substance from which the stand is to be constructed is poured into the opening and leveled smooth to the upper 90 edge of the sand. The base 9 is thus formed, its outer edges being studded with the ornamental pebbles or particles 8.

The base 9 having been thus formed, the hollow supporting column of the stand is 100 next constructed. In order to form the column of the stand, annular frames 10 and 11 are employed, being placed upon the base in proper location with the latter within the former, a space 12 being left between their walls. The frames 10 and 11 being in place the upper surface of the base 9 outside of the frame 10 is studded with pebbles or other ornamental particles 8, it being understood that the base will be sufficiently soft to 110

receive the same. This having been done, sand is packed into the frame 5 upon the base and around the outer walls of the frame 10 to a level with the top of frame 10. 5 Sand is also placed within the frame 11 to the top thereof forming a sand cylinder 7^a. After the sand has been sufficiently packed to hold its form, the frame 10 is gently elevated a considerable distance but not enough 10 to take it out of the sand 7. The wall of sand vacated by the frame 10 is now studded with pebbles 8, whereupon the frame 11 is elevated to the same height as the frame 10 and concrete poured into the space 15 12 forming a portion of the cylindrical column 13 of the stand. The frames 10 and 11 having been elevated as shown by the dotted lines in Fig. 5, sand is again poured into the mold and packed around the frame 20 10, being likewise poured into the frame 11 to raise the height of the cylinder 7^a. The frames are again elevated and the wall of sand vacated by the frame 10 is studded with pebbles as heretofore described whereupon 25 the concrete is poured into the space 12 to form another portion of the cylindrical column 13 of the stand. These steps are repeated until the column has been raised to a sufficient height. Such additional frames 30 5 as may be necessary are used.

In Fig. 6, the method of forming the top of the column is illustrated. The frames 10 and 11 have been removed, it being understood that the heights of the sand cylinder 35 7^a, the walls 13 and the sand at the outside thereof are equal. A frame 14 of annular or other form the size of the top of the column is placed above the top of the walls 13 and properly positioned with respect thereto. A small ring 15 is then 40 placed upon the sand cylinder 7^a in a central position at the upper end thereof, after which sand is built up around the outer edges of the frame 14 to the top edge thereof, and packed firm. Sand is also poured 45 within the ring 15 and firmly packed. The frame 14 is then removed and the inner wall of sand is studded with pebbles or other ornamental particles 8 as described in connection 50 with the base and columns after which concrete is poured into the space 16 to form the top 17 of the column 13. The ring 15 may be either removed or left in its opening 18 as desired. The purpose of this opening 55 is to permit the sand within the column forming the cylinder 7^a to be dumped out after the top of the column has been formed. This opening 18 has a further function which will be pointed out hereinafter.

60 The next step after the formation of the top of the column is to form the pedestal 24 for supporting the bowl 29. In the formation of this pedestal 24, another frame 5^c is used which is similar in all respects to the 65 frames used in the construction of the col-

umn. A spider 19 is placed upon the top of the frame and supports from its underside a form 20 which latter is secured to the spider by means of screws 21 or other suitable fastening means. The spider 19 with 70 its depending form 20 having been positioned upon frame 5^a, sand is packed within the mold to the top edges thereof, the form 20 making a depression in the sand the size of the pedestal. The form 20 has a central 75 vertical opening which permits the reception of a pipe 22, which latter is provided at its bottom end with a plurality of lateral branches 23 which form the support for the bowl 29 as will presently appear. The pipe 20 80 fits loosely within the form 20 so that it will remain in the sand after the spider with its form has been removed. The form 20 having been removed, the wall of the depression is studded with pebbles or other 85 particles 8 whereupon the depression is filled with concrete to form the pedestal 24. The pipe 22 will now be firmly cemented into the pedestal and will provide a means 90 of communication therethrough.

The pedestal 24 is the third of the units to be formed, but if desired it can be made first and allowed to set until the column 13 has been completed.

The pedestal 24 having been made, its 95 frame 5 is inverted and placed upon the uppermost frame 5, the pedestal resting upon the top 17 of the column 13, and the pipe 22 registering with the ring 15 closing the opening 18 in the top of the pedestal.

The next operation is the formation of the bowl 29. A plug 27 is first placed in the upper end of the pipe 22 to prevent sand or concrete from entering therein. A quantity 100 of sand must be scooped out from around the branches 23 of the pipe 22 to form a depression for the reception of a sectional semi-spherical form 26 for outlining the lower portion of the bowl wall 29. It has been found preferable to make this form 26 105 sectional so that it may be fitted around the branches 23 of the pipe. The upper portion of the wall of the bowl is designed by means of a form 25 which is suspended from a spider 19^a by means of screws or other fasteners 21^a in a manner similar to the form 20 described in connection with the formation of the pedestal 24. An additional frame 5^c is added to support the spider 19^a. The spider 19^a with its form 25 being in place, 110 sand is filled in around the edges thereof and firmly packed to design the outer wall portion of the bowl. Pebbles will of course be placed upon the top of the column 13 around the space to be occupied by the pedestal 24 before the latter is placed thereon. The outline of the bowl of the stand having been designed by the forms 25 and 115 26, these latter are removed and the recess 120 in the sand studded with pebbles or other 125 particles 8.

ornamental particles in any preferred design, after which a small quantity of concrete is poured in, it being sufficient to cover the branches 23 of the pipe 22. Sand 7 is then poured in on top of the cement a little at a time and molded as shown in Fig. 9 to form a circumferential channel 28 equidistant from the pebble-studded wall of the recess. Concrete is poured in this space 28 to the level of the sand. The sand 7 is gradually built up along the dotted lines in Fig. 9, concrete being poured into the space 28 a little at a time as previously described, and the bowl of the stand is completed in an obvious manner.

From the foregoing description read in connection with the accompanying drawings, the method of construction of my improved stand will be readily apparent. The pedestal 24 and the top 17 of the column being relatively soft when applied to each other will adhere together firmly so as to make the stand a solid unit. The branches 23 serve to stiffen the bowl and render it an integral part of the pedestal 24.

The bowl 29 is adapted for the reception of earth in which growing plants or flowers may be placed. In order to assure a supply of moisture through the earth to be placed inside of the bowl 29, I have provided the filler tube 32, the mouth of which rests just below the rim of the bowl, while its stem follows the contour of the rim and opens into the top of the pipe 22 thus permitting water to be introduced through the mouth of the tube and down into the open interior of the column 13. A hole 34 may be drilled in the lower portion of the column wall and closed by a plug to permit draining off of the water from within the column as desired. A wick 33 of any suitable material may be disposed into the column 13 from the top thereof which will assist in keeping the earth within the bowl moist.

This invention is capable of many changes and modifications which will immediately suggest themselves to those skilled in the art and I therefore wish it understood that I do not limit myself to the exact details as set forth but only to the spirit and scope of the invention as defined by the following claims.

Having thus described my invention, what I claim as new and desire to secure by Letters Patent is:—

1. The method of forming ornamental articles from plastic material comprising the successive formation of parts of said article by the formation of depressions in molding sand the walls of said depressions defining the outer contour of said parts, then embedding ornamental objects in the walls of said depression, pouring plastic material into said depressions and uniting said parts in assembled relation while in a semi-plastic condition.

2. The method of forming a stand having a hollow support, comprising forming a depression in molding sand to define the outer contour of a base, lining the inner walls of said depression with ornamental particles, filling said depression with plastic material, next forming a sand column upon the formed plastic material and building a sand wall about said base in spaced relation to said sand column, studding the sand wall with ornamental particles, filling the space between the sand wall and column with plastic material, next building sand above the top of the walls of the support thus formed from the plastic material and forming a depression in said sand, lining the wall of the depression with ornamental particles and filling said depression with plastic material to form the top of the stand, maintaining an opening in the plastic material in the top, next forming a depression in molding sand in the shape of a bowl lining the wall of the depression with ornamental particles and a plastic material while maintaining an opening in the bottom, and then filling the concrete lining with sand periodically.

3. The method of forming a stand having a hollow support, comprising forming a depression in molding sand to define the outer contour of a base, lining the inner walls of said depression with ornamental particles, filling said depression with plastic material, next forming a sand column upon the formed plastic material and building a sand wall about said base in spaced relation to said sand column, studding the sand wall with ornamental particles, filling the space between the sand wall and column with plastic material, next building sand above the top of the walls of the support thus formed from the plastic material and forming a depression in said sand, lining the wall of the depression with ornamental particles and filling said depression with plastic material to form the top of the stand, maintaining an opening in the plastic material in the top, next forming a depression in molding sand in the shape of a bowl, lining the wall of the depression with ornamental particles and a plastic material while maintaining an opening in the bottom, and then periodically filling the concrete lining with sand, cementing the bowl, before the plastic materials have set, to the top of the stand, then removing the sand from the bowl by the openings in the bowl and the stand.

4. The method of forming a stand, comprising the sectional formation of a mold, studding the interior of said mold sections with ornamental particles, pouring plastic material into said mold sections to form the various portions of said stand, and assembling said mold sections while the various sections of the stand body are in a semi-

- plastic condition, and permitting said assembled mold sections to stand until the various portions of the stand have become united and hardened.
5. A stand of plastic material having a base portion comprising a hollow column having an outlet opening therein, a pedestal mounted upon said column and retained in place thereon, said pedestal having a 10 communicating duct opening therethrough and into the interior of said column, a bowl supported by said pedestal and into which said pedestal duct communicates, retaining elements carried by said pedestal and embedded in said bowl for supporting and stiffening the same.
6. A stand of plastic material having a base portion comprising a hollow column having an outlet opening therein, a pedestal 20 mounted upon said column and retained in place thereon, said pedestal having a communicating duct opening therethrough and into the interior of said column, a bowl supported by said pedestal and into which 25 said pedestal duct communicates, retaining
- elements carried by said pedestal and embedded in said bowl for supporting and stiffening the same, and a pipe carried by said bowl adjacent one side thereof and opening into said duct for introducing water into said column.
7. A stand of plastic material having a base portion comprising a hollow column having an outlet opening therein, a pedestal mounted upon said column and retained in place thereon, said pedestal having a communicating duct opening therethrough and into the interior of said column, a bowl supported by said pedestal and into which said pedestal duct communicates, retaining 40 elements carried by said pedestal and embedded in said bowl for supporting and stiffening the same, and strips of absorbent material disposed in said duct and extending from said bowl into the interior of said column.

In testimony whereof I affix my signature.

ALLEN A. LYON.
